SWINEEN BRAMLEY-MOORE, OF WHITE PLAINS, NEW YORK, AND JOHN MCINTYRE,
OF PORTOBELLO, SCOTLAND.

CRUSHING MACHINE.

Application filed February 17, 1925, Serial No. 9,811, and in Great Britain December 1, 1924.

The present invention relates to machines or apparatus for refining pastes, liquids and semi-liquids, such as chocolate, paints, and the like, wherein the refining is accomplished by a grinding or crushing action between a roll or rotary device and a bed.

It is an object of the invention to provide a refining machine comprising a cooperable roll and bed wherein the cooperable grinding or crushing surfaces of the roll and bed are of novel formation and construction in order to increase the efficiency and capacity of the machine.

Another object of the invention is the provision of a roll and bed construction by means of which the material to be refined is caught under the roll and more effectively dealt with as compared with a plain roll working on a flat or smooth bed.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a view, partly in side elevation and partly in section, of a roll and bed embodying the improvements.

Fig. 2 is a section on the line 2—2 of Fig. 1.

Figs. 3 and 4 are views similar to Fig. 1 illustrating modifications.

Fig. 5 is a plan view illustrating still another modification.

Fig. 6 is a vertical section on the line 6—6 of Fig. 5.

Referring to Figs. 1 and 2, there is shown therein a roll 10 working on a bed 11, and, in carrying out the invention, the roll has a periphery composed of rods or members 12 of cylindrical form and disposed in an annular series with their axes parallel to the axis of the roll. The roll and crushing or grinding members 12 thereof may be of any desired size. The bed 11 includes a rack 13 having transverse concaved grooves 14 in the upper surface thereof into which the members 12 can fit snugly, said grooves being curved to correspond to the peripheries of said members 12. As shown, the rack 13 is set in a channel 15 of a container

or vessel 16 which holds the material to be refined, in order that such material will flow or run into the grooves 14 under the roll. As shown, the bed 11 is straight for relative rectilinear movement between the bed and roll, and the rolling action is either obtained by the movement of the roll back and forth over the bed, or by the reciprocation of the bed under the roll, the members 12 engaging in the grooves 14 similar to the engagement of the teeth of a gear pinion with the teeth of a gear rack.

In the embodiment as shown, the roll 11 is composed of a body 17 and side plates 18, said plates being of slightly larger diameter than the body to project beyond the periphery of the body. The periphery of the body has transverse grooves 19 in which the members 12 are seated, and said members have the square or non-circular lugs 20 at their ends seated in similarly shaped apertures 21 in the plates 18, thereby holding the members 12 assembled with the body 17 in a substantial and rigid manner. The edge portions of the plates 18 also provide annular flanges to overlap the opposite edges of the rack 13 to assist in confining the material between the roll and rack. The body 17 is of a dimension longitudinally of its axis equal to the length of the members 12, so that said members in seating in the grooves 19 may be subjected to considerable pressure without springing or yielding. Furthermore, the body 17, conceals the inner portions of the members 12, so that only the outer portions thereof are exposed, thus preventing the material from getting behind said members 12. The ridges or ribs on the periphery of the body 17 between the grooves 19 extend between the members 12, thereby bracing said members against springing or yielding movement toward one another, as well as closing the spaces or slots between said members. By separating the side plates 18, the members 12 are loosened in order that they may be turned about their axes to different positions, thereby increasing the life of said members, inasmuch when the exposed surfaces thereof have been worn said members may be adjusted to present the other surfaces thereof to engage the bed.

When the rolling action between the roll and bed occurs the rods or members 12 move into and out of the grooves 14 and have

partial turning movements in said grooves, thereby increasing the effective grinding surfaces between the roll and bed for any given diameter of roll. Furthermore, the material is caught in the grooves 14 under the roll so as to be given an effective crushing or grinding action between the convexed or cylindrical surfaces of the members 12 and the concaved surfaces of the grooves 14. 5 This will avoid the material being washed or carried away from between the roll and bed, as occurs between a plain roll and a smooth or flat bed, inasmuch as the material in the grooves 14 will remain therein 10 as the members 12 move down into the grooves.

The same action occurs if the roll has a complete or only a partial rotation.

As shown in Fig. 3 the bed 11 can be 20 curved with the roll on the concaved top surface thereof, and said bed may constitute the rim of a rotary drum or wheel. Fig. 4 shows the roll working on a bed which is convexed, and such bed may be the rim or 25 periphery of a drum or wheel with the roll 10 working on the top thereof.

The bed may also be of annular form to rotate about a vertical axis, or to permit the roll to roll on the bed along a circular path. 30 Thus, as shown in Figs. 5 and 6 the bed 11' constitutes a wheel rotatable about a vertical axis, and the rack 13' is of annular form, being set in an annular channel 15' of a rotatable container or vessel 16'. The roll 10' and rack 13' engage one another similar to bevel gears, whereby they can rotate about horizontal and vertical axes, respectively. The roll 10' is of conical form, the members 12' and grooves 14' being tapered so as to fit together snugly as the roll 40 and rack have rolling contact.

Having thus described the invention, what is claimed as new is:—

1. A crushing roll having its periphery composed of a series of members of circular cross section, a body within said series of members having portions fitting between and against said members throughout their length, and means normally preventing said members rotating about their axes. 45

2. A crushing roll having its periphery composed of a series of members of circular cross section, a body within said series of members having portions fitting against and 55 concealing the inner portions of said members throughout their length, and means normally preventing said members rotating about their axes.

3. A crushing roll having its periphery composed of a series of members of circular cross section, a body within said series of members against which said members seat throughout their length, and means normally preventing said members rotating 60 about their axes.

4. A crushing roll having its periphery composed of a series of members of circular cross section, a body within said series of members having grooves receiving said members throughout their length, and means normally preventing said members rotating about their axes. 70

5. A crushing roll having its periphery composed of a series of members of circular cross section, and means for holding said members assembled connected therewith in a manner to normally prevent the rotation of said members about their axes and to enable said members to be adjusted about their axes to present different surfaces thereof. 75 80

6. A crushing roll having its periphery composed of a series of members of circular cross section, and side plates between which said members are disposed, said members having terminal portions removably and adjustably engaging said side plates for the adjustment of said members about their axes. 85

7. A crushing roll having its periphery composed of a series of members of circular cross section, and side plates between which said members are disposed, and having angular openings therein, said members having angular terminal portions engaging in said openings and enabling said members to be 90 adjusted about their axes to expose different surfaces thereof.

8. A crushing roll comprising a series of members of circular cross section constituting the periphery of the roll, side plates between which said members are disposed, said members having terminal portions engaging said plates, and a body between said side plates bearing against the inner portions of said members throughout their length. 100 105

9. A crushing roll comprising a series of members of circular cross section constituting the periphery of the roll, side plates between which said members are disposed, said members having terminal portions engaging said plates, and a body between said side plates having portions fitting between said members throughout their length. 110

10. A crushing roll comprising a series of members of circular cross section constituting the periphery of the roll, side plates between which said members are disposed, said members having terminal portions engaging said plates, and a body between said side plates and concealing the inner surfaces of 115 said members throughout their length. 120

11. A crushing roll comprising a series of members of circular cross section constituting the periphery of the roll, side plates between which said members are disposed, said members having terminal portions engaging said plates, and a body between said side plates having grooves in which said members are seated throughout their length. 125

12. A crushing roll comprising a series of 130

members of circular cross section constituting the periphery of the roll, side plates between which said members are disposed and having angular openings, said members

5 having angular terminal portions engaging in said openings and enabling said members to be adjusted about their axes, and a body

between said plates having grooves receiving said members.

In testimony whereof we hereunto affix 10 our signatures.

SWINFEN BRAMLEY-MOORE.
JOHN McINTYRE.
